L. L. FREUND,
DOOR LATCH,
APPLICATION FILED MAY 8, 1920.

Patented Apr. 25, 1922.

UNITED STATES PATENT OFFICE.

LOUIS L. FREUND, OF SPOKANE, WASHINGTON.

DOOR LATCH.

1,413,979.

Specification of Letters Patent. Patented Apr. 25, 1922.

Application filed May 8, 1920. Serial No. 379,797.

To all whom it may concern:

Be it known that I, LOUIS L. FREUND, a citizen of the United States, residing at Spokane, in Spokane County and State of Washington, have invented certain new and useful Improvements in Door Latches, of which the following is a specification.

My present invention relates to improvements in door locks of that type employing a spring projected sliding bolt operable by cam movement accomplished through the medium of an element adapted to be pushed or pulled for the purpose of retracting the bolt to release the door.

The primary object of the invention is the provision of a device of this character that is comparatively inexpensive in first cost and composed of a minimum number of parts for performing its functions in a facile manner; which may be applied to a door and the door frame with slight expenditure of time and labor, and which is operable from either side of the door by a simple push or pull on the actuating handle.

With these objects in view the invention consists in certain novel combinations and arrangements of parts as will be hereinafter more specifically pointed out and claimed.

In the accompanying drawings one complete example of the physical embodiment of my invention is illustrated wherein the parts are combined and arranged according to the best mode I have so far devised for the practical application of the principles of my invention.

Figure 1 is a sectional view on a horizontal plane through a door and part of the frame showing the lock of my invention applied thereto, parts of the device also being shown in section for convenience of illustration.

Figure 2 is a vertical sectional view showing a portion of a door, and part of the lock in section.

Figure 3 is a perspective view of the slide bolt.

In the preferred form of the invention as shown in the drawings I have illustrated a portion of the door 1 and a part of the door frame 2, the door being mortised as at 3 and 4, these mortises extending respectively from the free edge of the door in a horizontal plane a sufficient distance into the stile of the door, and the second mortise, of smaller diameter extending transversely

through the door and intersecting the larger mortise 3.

The spring projected, slide bolt, of the device is indicated as a whole by the number 5, and is of cast metal with a cylindrical or rounded body 6 having a reduced latch head 7 of conventional form, while at the rear of the bolt a reduced, cylindrical extension 8 is provided, all these elements being integral. Extending transversely through the body of the bolt toward the rear end thereof, is an open slot 9, at one end of which is formed an interior, wedge shaped lug 10 provided with opposed, diverging cam faces 11 and 12, and extending from the top of the bolt is fashioned a vertical socket 13 which terminates in the integral lug portion of the bolt.

Within the mortise 3 is located a metallic barrel or case 14, cylindrical in cross section to conform to the bolt and firmly secured in the mortise to house and guide the spring projected, reciprocable bolt, which is forced to locked position by the coil spring 15 disposed in the end of the barrel and surrounding the rear extension 8 of the bolt. The spring bears against the shoulder 16 of the bolt and as the bolt is retracted the spring is compressed between the shoulder 16 and the closed end of the barrel 14, the tendency of the spring being to urge the bolt outwardly or project it to locked position.

The open end of the mortise 3 is finished with a mortise plate 17, and the transverse mortise 4, at its ends is provided with rings 18, to afford a neat and finished appearance for the members.

At 19 the usual mortise is provided in the door frame and finished with the mortise plate 20 to receive and coat with the head 7 of the slide bolt in usual manner.

As before stated the slide bolt is spring projected, and it is positively retracted through the action of a push or pull shank 21, reciprocable laterally of the door through the mortise 4 and guided in its movement by the end plates 18 of the mortise. The shank is preferably rectangular in cross section, of oblong shape, and at its ends, at either side of the door is provided with suitable handles 22 and 23, of duplicate construction, and secured to the ends of the body of the shank by screws 24. The shank is preferably of metal, and at one side is centrally cut away, or cast with a cam 110

groove of V-shape 25 in one edge, the two cam faces 26 and 27 of the groove conforming to the angle of the two faces of the wedge shaped lug in the slot of the slide bolt, as seen in Figure 1.

For the purpose of locking the bolt against retraction, I may employ a typical key operated locking device 28 which includes a cylindrical lock bar 29 to engage in the socket 13 of the bolt.

In Figure 1 the bolt is held in projected position by the spring 15, and the door is secured with relation to the door frame or door jamb by engagement of the bolt head 15 in its mortise 19 in the frame. The bolt may be retracted from either side of the door, by either a push or a pull applied to either of the handles 22, 23. If a push is applied to the handle 23, the shank is shoved in its mortise and the frictional engagement between the faces 12 and 27 results in pushing the bolt to the left in Figure 1 to retract it from the mortise 19, and as the bolt head is withdrawn from the mortise, the continued push 25 on the handle swings the freed door on its hinges to open the same. The movement of the shank, in either direction, is limited by contact of the end handles with the door face, which encounter the door before the 30 cam face of the shank can pass over the apex of the wedge shape lug 10 of the bolt 5.

As the bolt is retracted, the spring 15 is compressed between the shoulder 16 of the bolt and the end of the barrel, and the instant 35 the pressure is released on the shank, the resiliency of the spring forces the bolt to

the right in Figure 1 causing the wedge shape lug to move the shank laterally to normal position, and project the bolt to extended position. The door may be pulled to 40 closed position and the bolt simultaneously retracted, and then projected when the pull is released from the handle 23, or the bolt may be retracted against the tension of the spring 15 as the beveled bolt head slides over 45 the plate 20 of the door frame, after which the bolt is projected into the mortise 19 in usual manner.

From the above description taken in connection with my drawings it is evident that 50 I have provided a door lock device which will perform its functions with comparative perfection, which is durable, facile in operation and withal comparatively inexpensive of production, and readily adapted for use. 55

Having thus fully described my invention, what I claim as new and desire to secure by Letters Patent is—

The combination with a door having a mortise and barrel therein, of a spring projected bolt fashioned with a slot having one wall formed as an interior wedge-shaped cam lug, a shank angular in cross section and transversely reciprocable in said bolt, said shank having a notch to form cam faces 60 complementary to said lug, handles on the ends of the shank, a reduced extension and shoulder formed at the rear end of the bolt, and a spring interposed between said shoulder and the closed end of said barrel. 70

In testimony whereof I affix my signature.
LOUIS L. FREUND.
